UNITED STATES PATENT OFFICE.

EVAN O. EDWARDS, OF CHEHALIS, WASHINGTON.

LOCKING CLAMP-BOLT.

1,082,461.

Specification of Letters Patent. Patented Dec. 23, 1913.

Application filed March 10, 1913. Serial No. 753,202.

To all whom it may concern:

Be it known that I, EVAN O. EDWARDS, citizen of the United States, residing at Chehalis, in the county of Lewis and State 5 of Washington, have invented a certain new and useful Improvement in Locking Clamp-Bolts, of which the following is a specification.

My invention relates to improvements in 10 rail-joints and its object is to provide simple and effective means whereby fish-plates may be securely fastened and held in their proper position against the sides of abutting rails without the use of screw-threaded bolts 15 and nuts that have been used heretofore. I attain these objects by devices illustrated in the accompanying drawings, wherein—

Figure 1 is a view in side elevation of a rail-joint embodying my invention, Fig. 2 20 is a view of the same in horizontal section on broken line *x*, *x* of Fig. 1, and Fig. 3 is a view of the same in vertical section on the broken line *y*, *y* of Fig. 1.

In the accompanying drawings wherein 25 like reference numerals denote like parts, 5, 5 are ends of two abutting rails whose webs are provided with slotted holes each of which holes is enlarged at one of its ends sufficiently to allow the knob 8 on the end of 30 a bolt 9 to pass through it, the smaller slotted portion of the hole being only large enough to allow the body of the bolt to move freely within it.

10, 10 are fish-plates of the usual type 35 disposed on either side of the abutting rails 5, each having slotted holes 11 and 12 respectively, similar to, and disposed to register with, the slotted holes 6 in the webs of the rails 5.

13, 13 are wedge shaped plates each of 40 which has a slotted hole 14 extending longitudinally thereof and each of which slotted holes is enlarged at its end nearest the thin end of the wedge shaped plate 13 to permit 45 the passage through it of the knob 8. Each wedge shaped plate 13 is provided with teeth on its inclined surface, as illustrated in Fig. 2, and each slotted hole 14 has its outer edge 15 rounded off to fit the curved surface 50 of the knob as illustrated in Fig. 3.

In the construction of my rail-joint one 55 of the fish-plates 10, 10 is placed on each side of the two rail ends 5 in the usual manner, the slotted holes 11 and 12 being made to register with the slotted holes 6, 6 respectively. Threadless bolts 9, each having a

knob 8 at one of its ends, are thrust through the enlarged portion of the slotted holes until the head of the bolt 9 rests against one of said fish-plates 10 and the knob end of the bolt projects outwardly from the other of said fish-plates. One of the wedge shaped plates 13 having a slotted hole 14 is so placed on the projecting end of the bolt 9 that its smooth flat surface rests against the fish-plate 10 while the inclined toothed surface of a similar wedge shaped plate 13 is oppositely disposed on the bolt 9. The knobs 8 having been thrust through the enlarged portions of the slotted holes of the wedge shaped plates 13, said plates 13 then may be moved to bring the bolts 9 within the smaller portions of the slotted holes 14, thus causing the knob 8 to act as a head to hold the plates 13 together. Any desired tension may then be brought on the bolt 9 by hammering on the large ends of the plates 13 to cause said plates 13 to wedge tightly together, in which positions they are held by the teeth on their opposed surfaces.

In that form of my invention illustrated in the accompanying drawings, two bolts only are shown as holding the fish-plates, but, obviously, any desired number may be used in connection with each joint.

If the rail-joints become loose when subjected to use it is easy to tighten them by hammering on the ends of the wedge shaped plates 13.

Obviously the holes through the fish-plates and the holes through the webs of rails need not be oblong, but they must be large enough to permit the head or knob 8 of one end of a bolt to pass through them.

Manifestly minor changes in the details 95 of construction of my invention may be made within the scope of the appended claims without departing from the spirit thereof or sacrificing any of its advantages.

What I claim is:

1. In a rail-joint of the class described, the combination with a pair of fish-plates each fish-plate of which pair is provided with a plurality of oblong bolt-holes that are each enlarged in one portion to permit 105 the passage of a bolt-head through such enlarged portion, and each of which fish-plates is adapted to be disposed against the webs of abutting end portions of rails, of a plurality of threadless double-headed bolts, and 110 a pair of wedges each wedge of which is provided with an oblong hole enlarged in one

portion and each of which is further provided with a serrated surface on one of its sides whereby said double-headed bolts may be disposed in association with said pair of fish-plates and said wedges to form a rail-joint.

2. In a rail joint of the class described, the combination with a pair of fish-plates, each fish plate of which pair is provided 10 with bolt holes, of a plurality of double-headed bolts one head of each of which bolts is of a size to adapt it to pass through any of said bolt holes in said fish-plates and a plurality of pairs of wedges, one wedge of 15 each pair of which is provided with an oblong hole that is enlarged in one of its por-

tions to permit the smaller head of one of said bolts to pass through such enlarged portion of said hole, the engaging surface of each wedge of each pair being serrated 20 whereby when said surfaces of a pair of wedges are wedged together in their normal positions they may be interlocked to prevent an endwise movement of one wedge with respect to the other.

In witness whereof, I, hereunto subscribe my name this 25th day of February A. D., 1913.

EVAN O. EDWARDS.

Witnesses:

FRED W. KELLY,
FRANK WARREN.
